R. J. BURHEN.

CORNER BRACKET AND FASTENER FOR SCREEN FRAMES AND THE LIKE.

FILED MAR. 22, 1922.

UNITED STATES PATENT OFFICE.

REINHART JACOB BURHEN, OF ST. LOUIS, MISSOURI, ASSIGNEE OF ONE-HALF TO
WALTER P. RIESTER, OF ST. LOUIS, MISSOURI.

CORNER BRACKET AND FASTENER FOR SCREEN FRAMES AND THE LIKE.

Application filed March 22, 1922. Serial No. 525,698.

To all whom it may concern:

Be it known that I, REINHART J. BURHEN, a citizen of the United States, and a resident of St. Louis, in the State of Missouri, have invented certain new and useful Improvements in Corner Brackets and Fasteners for Screen Frames and the like, of which the following is a specification.

My present invention relates generally to screen frames and more particularly to means for fastening the corners thereof, my object being the provision of a simple device by means of which the corners of screen frames may be rigidly connected and in such manner as to obviate the necessity of a skilled mechanic in the assembling operation.

A still further object is the provision of a simple inexpensive device which may be readily and cheaply manufactured and by means of which the side and end rails of screen frames may be rigidly and permanently connected in butt joint relation so as to avoid the necessity of skilled workmen.

In the accompanying drawing which illustrates my present invention and forms a part of this specification,

Figure 1 is a perspective view illustrating the practical application of my invention in a joint,

Figure 2 is a vertical section through the joint shown in Figure 1,

Figure 3 is a horizontal section through a portion of the joint, and

Figure 4 is a detail perspective view of the brace and fastener removed.

Referring now to these figures and particularly to Figures 1, 2 and 3 my invention proposes the utilization of rails 10 and 11 in the formation of screen frames and the like, having lengthwise grooves 12 in the opposite faces thereof, extending along and in parallel adjacent relation to the side edges thereof and my invention further proposes the formation of a screen frame by means of the rails 10 and 11 disposed in the butt jointed relation shown in Figure 1 so as to avoid the necessity for more or less skillful mitering.

For use in connection with rails and a joint of the above described type my invention proposes a brace and connecting member which as seen particularly in Figure 4 is formed from a single piece of sheet metal with parallel side plates 13 and 14 bent an-

gularly in the same direction from opposite sides of a flat connecting or base portion 15, these side plates 13 and 14 having along their side edges inturned flanges 16 adapted to extend into the grooves 12 of one of the abutting rails, for instance the rail 10 in the joint shown in Figure 1. For this purpose the side plates 13 and 14 are spaced apart a distance adapted to receive one end of the rail 10 therebetween, the extremity of the rail 10 being seated on the flat connecting or base piece 15 as clearly shown in Figures 1 and 2.

The side plates 13 and 14 also have apertures 17 to receive screws and the like 18 extending into the material of the rail 10 as shown in Figure 3 so as to secure the side plates in their embracing relation to the rail 10.

In the formation of the side plates 13 and 14, their central portions are struck-out therefrom and bent in parallel relation from opposite sides of the connecting or base piece 15 and in a direction opposite to the extension of the side plates 13 and 14, to form side wings 19 adapted to embrace the side surfaces of the rail 11 against which the end of the rail 10 with the connecting or base piece 15 seats. Each of these side wings 19 is also provided with an integrally struck-up tongue 20 projecting at right angles thereto and bent inwardly, the two tongues being in opposing relation and so spaced from the base or connecting piece 15 as to be engageable within the adjacent groove 12 of the rail 11 as clearly shown in Figures 1 and 2.

Like the side plates 13 and 14, the oppositely extending rail embracing wings 19 have apertures 21 adapted to receive screws and like fastening members 22 extending into the material of the rail 11 and thus it is obvious that the complete joint will be rigid and permanent and may be completed with but slight instruction in the hands of unskilled persons.

I claim:

A brace and connecting member for similarly formed angular rails in butt jointed relation having parallel grooves in their side faces adjacent to their opposite edges, consisting of a section of sheet metal having a base piece and parallel side plates extending in one direction from the base piece of less width than said rails and adapted

2
to embrace one end of a rail disposed there-
between and in endwise engagement with
the base piece, said side plates having in-
5 turned flanges along their opposite sides
adapted to project into the grooves of the
said rail end and also having apertures for
the reception of fastening screws and the
like, side wings struck-up from the said side
10 plates and extending in parallel spaced re-
lation from the said base piece in the oppo-

site direction to said side plates to trans-
versely embrace opposite sides of the other
rail and having integral tongues struck-
up therefrom and projecting transversely
thereof for insertion within certain of the 15
grooves of the last mentioned rail said wings
having portions extending beyond the said
tongues and provided with apertures for
the reception of fastening means.

REINHART JACOB BURHEN.
